UNITED STATES PATENT OFFICE.

DANIEL KING, OF FINKSBURG, MARYLAND.

HAY-RACK.

SPECIFICATION forming part of Letters Patent No. 558,498, dated April 21, 1896.

Application filed June 4, 1895. Serial No. 551,861. (No model.)

To all whom it may concern:

Be it known that I, DANIEL KING, a citizen of the United States, residing at Finksburg, in the county of Carroll and State of Maryland, have invented a new and useful Hay-Rack, of which the following is a specification.

The invention relates to improvements in hay-racks.

10 The objects of the present invention are to simplify and improve the construction of hay-racks, to increase their strength, durability, and lightness, and to enable them to be conveniently mounted on and removed from their 15 running-gear.

The invention consists in the construction and novel combination and arrangement of parts hereinafter fully described, illustrated in the accompanying drawings, and pointed 20 out in the claims hereto appended.

In the drawings, Figure 1 is a perspective view of a hay-rack constructed in accordance with this invention. Fig. 2 is a central longitudinal sectional view. Fig. 3 is a transverse sectional view. Fig. 4 is a detail perspective view illustrating the manner of supporting the central beam on the bolsters. Fig. 5 is a detail perspective view of one of the posts, illustrating the manner of securing the 25 same to the bolster.

Like numerals of reference indicate corresponding parts in all the figures of the drawings.

1 I designates a central longitudinal I-beam 35 constructed of metal and detachably mounted on transverse bolsters 2, which are secured in the usual manner to front and rear axles 3 and 4. The I-beam is provided adjacent to each bolster with a substantially rectangular support 5, which is constructed of a single piece of metal and which is bent into substantially rectangular form, and which is provided at the inner side of the top with an attachment-plate that is bolted, riveted, or otherwise secured to the bottom flanges of the I-beam; but any other desired form of support may be employed for mounting the I-beam on the bolster. Each support 5 is provided at its outer side with a depending 40 tongue 6, preferably formed by an L-shaped plate, having one arm secured to the lower

face of the I-beam and the upper portion of the other arm attached to the adjacent side of the support 5, and the depending tongue 6 is arranged on the outer face of the bolster 55 2 and fits in a recess formed by plates 7, secured to the outer face of the bolster and arranged at the side edges of the tongue. The plates 7 have their inner portions angularly bent, as shown, to form a recess or socket for 60 the depending tongue 6. By this construction the central longitudinal I-beam is detachably mounted on the front and rear bolsters and may be readily lifted off the same when front and rear sections 8 and 9 of the 65 hay-rack are removed.

The front and rear sections 8 and 9 of the hay-rack are detachably mounted on and interlocked with the central longitudinal I-beam and are arranged to slide outward for 70 removal, and they are constructed substantially the same, with the exception that the parallel side bars 10 of the front section are disposed horizontally, as shown, while the side bars 11 of the rear sections are arched to 75 clear the hind wheels of the vehicle.

The side bars 10 and 11 of the front and rear sections 8 and 9 are connected by inner and outer transverse bars 12 and 13, and the side and transverse bars are preferably constructed of channeled metal. The sections are supported by centrally-arranged transverse braces 14, which are provided with central recesses 15, forming shoulders and receiving the upper portion of the central longitudinal 85 I-beam, and the inner and outer transverse bars are provided at opposite sides of the central longitudinal I-beam with lugs 16, engaging the upper flanges of the I-beam, and preferably formed by plates suitably secured to 90 the lower faces of the transverse bars. These lugs 16 interlock with the top flanges of the I-beam and are adapted to be disengaged therefrom by sliding the sections outward. Each section is provided at opposite sides of 95 the central longitudinal beam, at points adjacent to the sides of the hay-rack, with vertical posts 17, depending from the section and resting upon the adjacent bolster 2 and forming supports for the sections, and also projecting above the section to provide struts for truss-bars 18 and to serve as stops to give a 100

load a firm hold on the bottom or framework of the hay-rack to prevent any lateral movement or accidental shifting of a load of hay or other material when the hay-rack is traveling over inclined and uneven surfaces. The lower end of each post is provided with a depending attachment-plate 19, having a lower angular portion conforming to the configuration of the bolster 2 and detachably secured 10 to the same by a fastening device 20, which is adapted to be removed to enable the section to slide outward on the I-beam.

Each truss-bar 18 is inclined at opposite sides of the upwardly-projecting portion of 15 its post, and extends downward therefrom, and has its terminals connected with the inner and outer transverse bar, and also with a horizontal tie-bar 21. The tie-bar 21 is provided with a central opening 22 for the reception 20 of the post, and it may, as illustrated in the accompanying drawings, be constructed of two sections, with their central portions laterally offset to form the opening 22, or it 25 may be formed by a single bar provided with an opening, if desired. The truss-bar increases the holding power of the post in its action on the load, and it may be connected with the tie-bar at opposite sides of the post by short bars or plates 23.

30 Each section is supported at its outer transverse bar by a truss comprising a central rectangular strut 24 and opposite inclined truss-bars 25; but any other desired form of bracing may be employed to enable the sections 35 to withstand successfully the strain incident to their use.

The outer transverse bars of the sections are provided at their inner sides with perforated ears or lugs 26, arranged in pairs and 40 having detachably pivoted or fulcrumed between them the lower ends of standards 28, which are preferably constructed of channeled metal, but which may, if desired, be of any other desired form. The fastening devices 27 may be withdrawn, when it is desired 45 to detach the standards, to facilitate the removal of the hay-rack. Each standard is supported at its lower end by a pair of upwardly and inwardly inclined arms 29, which are preferably slightly curved and constructed of a single piece of metal and have a transverse connecting portion at their lower ends riveted, bolted, or otherwise secured to the upper face of the transverse bar. The arms 29 55 embrace the lower portion of the standard, which is secured at the desired inclination by a removable fastening device 30, adapted to be withdrawn to permit the standard to be folded down upon the section, when desired.

60 The standards mutually support each other, and those at each side are connected with each other and with the adjacent terminals of the inner transverse bars 13 by adjustable connections 31, preferably composed of links 65 to make the connections flexible. The adjacent ends of the link-rods 32 are shown in the drawings as passing loosely through perfora-

tions of the ends of the inner transverse bars 13 and connected by a turnbuckle 33; but the connections 31 may engage the ends of the 70 transverse bar or any other desired part of the sections by any other suitable means, such as a hook and chain, or any other well-known equivalent of a turnbuckle. This construction or connection between the standards and 75 the central portion of the rack produces the desired tension on the parts, and when a hook and chain is employed it will be apparent that the standard will form powerful levers to assist the operator in straining the parts 80 to the desired tension. The outer terminals of the connections 31 are pivoted to ears or lugs 34, projecting inward from the standards at points intermediate of the ends thereof.

The sections of the hay-rack are further 85 supported and strengthened by a series of stay-chains 35, located between and connecting the inner transverse bars and holding the sections against outward movement. Each stay-chain is composed of two sections, having 90 their outer terminals permanently attached to the inner transverse bars and their inner terminals adjustably connected together to enable the chains to be varied in length to correspond with the adjustment of 95 the sections and to secure the desired tension. The front standards are connected by upper and lower transverse rods 36, preferably composed of sections loosely or movably connected with the standards and adjustably 100 connected with each other.

A flexible ridge-pole support or ladder 37 is centrally arranged between the front standards and is connected with the upper transverse rod 36 and with the rectangular strut 105 24, and it is preferably composed of links arranged to form the sides and the transverse portions 38 to engage the ridge-pole.

The hay-rack is provided at its rear end with any suitable windlass-shaft 39 to permit 110 the rope or other connection of the rear end of the ridge-pole to be drawn to the desired tension.

It will be seen that the hay-rack is simple and inexpensive in construction, that it possesses great strength, durability, and lightness, and that it may be readily mounted on and removed from a running-gear, and that as it is separable into its various parts it may be readily detached from or mounted on 115 the running-gear by one man. It will also be apparent that as a single central longitudinal beam is employed, and that as the sections are supported in the manner shown, the front axle of the running-gear may be readily 120 turned without the front wheels coming in contact with any of the parts of the rack, except the central longitudinal beam, which will not interfere with the ordinary turning, and which is arranged to allow the front 125 wheels great latitude in cramping a hay-wagon.

Changes in the form, proportion, and the minor details of construction may be resorted

to without departing from the principle or sacrificing any of the advantages of this invention.

What I claim is—

- 5 1. In a hay - rack, the combination with transverse bolsters 2, of a central longitudinal beam detachably mounted on and interlocked with the bolsters and extending the entire length of the hay-rack, and a rack composed of sections and removably mounted on and supported by the longitudinal beam, substantially as described.
- 10 2. In a hay - rack, the combination with transverse bolsters 2, of a central longitudinal beam detachably mounted on and interlocked with the bolsters and extending the entire length of the hay-rack, the detachable hay-rack sections mounted on the longitudinal beam, and supports located at opposite sides 20 of the beam and depending from the rack and resting upon the bolsters, substantially as described.
- 15 3. The combination with transverse bolsters, of a hay-rack provided with posts depending from it and supported on the bolster, and projecting above the hay-rack to engage a load, substantially as described.
- 25 4. The combination of bolsters, a rack-section, posts depending from the sections and resting upon the bolsters and projecting above the sections and forming struts and adapted to engage a load, the truss-bars connecting the upper ends of the posts with the sections, and tie-bars connecting the ends of the truss-bars, substantially as described.
- 30 5. The combination of bolsters, hay-rack sections, posts located at opposite sides of the sections and depending therefrom and mounted on the bolsters and extending upward from the sections, the truss-bars connected with

the upper ends of the posts and with the sections, the tie-bars connecting the ends of the truss - bars, and the transverse braces connecting the posts, substantially as described.

6. The combination of bolsters, a longitudinal beam, the hay-rack sections mounted in the beam and provided with lugs arranged in pairs and engaging the beams, posts depending from the sections and supported on the bolsters, and transverse braces connecting the posts and provided with central shoulders receiving and engaging the longitudinal beam, substantially as described.

7. The combination with a longitudinal beam, removable hay-rack sections mounted thereon, the standards hinged at their lower ends to the outer ends of the sections and arranged at the corners thereof, and the continuous longitudinally-disposed connections between the standards arranged at the sides of the rack and engaging the inner ends of the sections, substantially as described.

8. The combination of a longitudinal beam, hay-rack sections provided with inner and outer transverse bars, the front and rear standards hinged at their lower terminals at the outer transverse bars and arranged at the sides of the rack, and the longitudinally-disposed adjustable connections between the front and rear standards engaging the ends of the inner transverse bars, substantially as described.

In testimony that I claim the foregoing as my own I have hereto affixed my signature in the presence of two witnesses.

DANIEL KING.
